(57) **CLAIM**

The ornamental design for a disc load cell, as shown and described.

DESCRIPTION

FIG. 1 is a top perspective view of a disc load cell of the invention.

FIG. 2 is a bottom perspective view thereof.

FIG. 3 is top view thereof; and,

FIG. 4 is a side view thereof.

The design is for a disc load cell which is used in a scale to weigh vehicles or other articles.
